TOWEL RACK

Helen E. Hulsey, 509 Greenfield Road, Kansas City, Mo.

Filed Apr. 12, 1960, Ser. No. 60,162

Term of patent 14 years

(Cl. D4—3)

Fig. 1

Fig. 2

FIG. 1 is a front perspective view taken from one side of a towel rack embodying my new design, and

FIG. 2 is a side elevational view thereof.

I claim:

The ornamental design for a towel rack, as shown.
